(57) CLAIM

The ornamental design for a financial services card, as shown and described.

DESCRIPTION

FIG. 1 is a front view of a first embodiment of our financial services card.

FIG. 2 is a back view thereof.

FIG. 3 is a top view thereof.

FIG. 4 is a bottom view thereof.

FIG. 5 is a right side view thereof.

FIG. 6 is a left side view thereof.

FIG. 7 is a front view of a second embodiment of our financial services card.

FIG. 8 is a back thereof.

FIG. 9 is a top view thereof.

FIG. 10 is a bottom view thereof.

FIG. 11 is a right side view thereof.

FIG. 12 is a left side view thereof.

FIG. 13 is a front view of a third embodiment of our financial services card.

FIG. 14 is a back view thereof.

FIG. 15 is a top view thereof.

FIG. 16 is a bottom view thereof.

FIG. 17 is a right side view thereof.

FIG. 18 is a left side view thereof.

FIG. 19 is a front view of a fourth embodiment of our financial services card.

FIG. 20 is a back view thereof.

FIG. 21 is a top view thereof.

FIG. 22 is a bottom view thereof.

FIG. 23 is a right side view thereof.

FIG. 24 is a left side view thereof.

FIG. 25 is a front view of a fifth embodiment of our financial services card.

FIG. 26 is a back view thereof.

FIG. 27 is a top view thereof.

FIG. 28 is a bottom view thereof.

FIG. 29 is a right side view thereof.

FIG. 30 is a left side view thereof.

FIG. 31 is a front view of a sixth embodiment of our financial services card.

FIG. 32 is a back view thereof.

FIG. 33 is a top view thereof.

FIG. 34 is a bottom view thereof.

FIG. 35 is a right side view thereof; and,

FIG. 36 is a left side view thereof.

The broken lines in FIGS. 1, 7, 13, 19, 25, and 31, showing a card chip, text, and a logo, are included for the purpose of illustrating environmental features of the financial services card that form no part of the claimed design.

1 Claim, 12 Drawing Sheets
